DESIGN FOR A TEAPOT

Ester L. Holmes, San Diego, Calif., assignor of one-half to Joseph E. Holmes, San Diego, Calif.

Application February 19, 1946, Serial No. 126,695

Term of patent 7 years

(Cl. D44—26)

To all whom it may concern:

Be it known that I, Ester L. Holmes, a citizen of the United States of America, residing at San Diego, in the county of San Diego and State of California, have invented a new, original, and ornamental Design for Teapot, of which the following is a specification, reference being had to the accompanying drawing, forming a part thereof.

Figure 1 is a top or plan view of my ornamental
design for teapot; and Fig. 2 is a side elevational view thereof.

I claim:

The ornamental design for a teapot, substantially as shown.

ESTER L. HOLMES.
